FINGER BOARD

Joseph O. Bennett, Mount Vernon, Ill.

Application February 28, 1945, Serial No. 580,195

7 Claims. (Cl. 214—1)

1

This invention relates to finger boards.

An object of the invention is the provision of a finger board for oil wells for supporting a plurality of pipes which may have been removed from the well or which are being applied to the string of pipes in a well, said finger board being movable toward or away from a platform so the operator may conveniently suspend the pipe sections in a convenient position for application to or removal from a string of pipes.

Another object of the invention is the provision of a finger board which may be positively shifted toward or away from the operator for filling the finger board with pipes removed from a well with the movement of the finger board positioning the pipes more conveniently for the operator, said finger board being so arranged that it may be shifted manually or by a power operated device.

A further object of the invention is the provision of a finger board which may be shifted longitudinally in either direction for placing the pipe supporting fingers in a convenient position for the operator, a platform being associated with the finger board for the support of the operator when placing the pipes in position on the board.

This invention will be best understood from a consideration of the following detailed description, in view of the accompanying drawings forming a part of the specification; nevertheless, it is to be understood that the invention is not confined to the disclosure, being susceptible of such changes and modifications as define no material departure from the salient features of the invention as expressed in the appended claims.

In the drawings:

Fig. 1 is a fragmentary view in side elevation of a finger board constructed according to the principles of my invention.

Fig. 2 is a plan view of the same.

Fig. 3 is an enlarged vertical section taken along the line 3—3 of Fig. 1.

Fig. 4 is a fragmentary enlarged horizontal section showing the guiding means for the finger board and its connection with a transverse bar.

Fig. 5 is a fragmentary view with parts broken away showing in elevation the finger board and the shifting means for said board.

Fig. 6 is a horizontal section taken along the line 6—6 of Fig. 5.

Fig. 7 is a vertical section taken along the line 7—7 of Fig. 5.

Fig. 8 is an enlarged plan view of a movable platform for the operator of the finger board.

Fig. 9 is a side view of the platform showing parts in section.

2

Referring more particularly to the drawings, 10 and 11 designate a pair of uprights forming part of a derrick structure for supporting a finger board above a drilling well. The supporting structure may consist of four posts, such as 10 and 11, located in spaced relation and formed of angle iron construction. These posts are braced and held together by horizontal bars 12 and 13. The structure is erected over the well and besides the uprights 10 and 11 and the brace bars 12 and 13, other bars may be employed for bracing the structure to maintain the weight impressed upon it.

A platform generally designated by the numeral 15 is formed of a plurality of planks 16 which are connected together by straps 17. The platform is of sufficient length so that it will rest upon a pair of cross braces 12 at the proper height with its inner edge at one side of the vertical center line of the derrick so that the operator may stand on the platform for properly positioning joints of well casings, well tubing or drill stems generally to be classified as pipes when they are delivered to him by elevators on the usual hoisting cables. Thereafter said pipes are placed in supported relation between the fingers 18 of a finger board. The platform is held in position on the bars 12 by means of bolts 20 (Fig. 9) which have their upper ends threaded and inserted through a passage 21 in one of the planks 16. A nut 22 threaded onto the upper end of the bolt will draw a U-shaped portion 23 of the bolt against the bottom edge of the angle iron or cross brace 12. After the platform is in position and at the proper height the nuts 22 are screwed up tight for securing the platform against movement.

One of the planks 16 is provided with an opening 25 which receives an eye 26. This eye is adapted to receive a hook connected with a chain or cable so that the platform 15 may be raised or lowered.

A chain generally designated by the numeral 27 has one end received by an eye 28 at the lower end of a bolt 29 which has a head 30 resting on the outer face of one of the planks 16. The other end of the chain is similarly connected to the plank and therefore the same reference numerals are applied to the bolt and the associated parts. This chain is employed for supporting tools used in pulling the sections of the pipe from the well otherwise handling such pipe sections. It will be noted that the bolts 29 are received by passages in the associated plank.

Extending transversely of the aforementioned

platform, preferably above it, at one end is the finger board comprising a frame which carries a series of spaced fingers and mechanism for moving them whereby the intervening spaces between adjacent fingers may be successively presented in alignment with the edge of the platform. The latter serves to guide a selected number of stands of pipe into each space. The frame also carries at one of its ends means for moving the carrier on which said fingers are mounted and at its other end the intermittently operated driving devices by means of which the guide is actuated step-by-step. The frame comprises a tubular guide bar 35 connected to plates 36 which are in turn attached to the respective bars 13 adjacent one end of the supporting structure. The tubular member 35 is provided with a pair of diametrically disposed longitudinal slots 37 through which extend the pipe rack fingers 18 after passing through the perforations 38 in a bar or tubular member 39 slidably mounted in the tubular member 35. Nuts 40 are secured to the outer ends of the fingers at one side of the tubular member 35 for maintaining the fingers in position. The longer portions of the fingers extend through the slot and sections of the pipe are adapted to be placed between the fingers and supported preparatory to stringing the pipe in the well or after the sections have been detached from the string remaining suspended in the well.

Posts 41 are secured to the guide or track 35 and extend upwardly. The free ends of these posts are provided with bearings 42 to receive a shaft 43.

Ring gear 44 is secured to the inner end of the shaft 43 while a pinion 45 is secured to the other end of the shaft.

A gear 46 meshes with the gear 45 and has a centrally disposed threaded passage received by a threaded end 47 of a rod or shaft 48 which is located within the member 35 and has its inner end secured to the member 39.

As shown more particularly in Fig. 5, the gear 46 is provided with a hub 50 having an annular groove 51 which is received by the lugs 52 on the outer ends of the arms or fingers 53 which are secured at 54 to the outer end of the guide or track 35. A thrust bearing 55 is located on the rod 48 in connection with the hub 50. By this construction the gear 46 may be revolved in substantially a vertical plane by the gear 45 but will be maintained against lateral displacement. Rotation of the gear 46 will cause the rod 48 to be drawn in a direction depending upon the direction of rotation of the gear 46 for shifting the member 39 toward or away from the platform. Fingers 18 will be shifted toward or away from the platform 15 as desired.

A motor 60 is secured to the guide 35 at one side of the gear 44 for driving a shaft 61 and a gear 62 secured to the said shaft. The gear 62 meshes with the ring gear 44 for not only rotating the ring gear, but the shaft 43 and likewise the gears 45 and 46.

Finger boards are normally held in a definite position adjacent a well so that it is necessary for the operator when removing sections of pipe from a well or applying the sections to the string in a well to move back and forth along the finger board for placing the sections of the pipe between the fingers 18.

In the present construction the finger board is moved toward or away from the platform 15 so that the spaces between adjacent fingers can be placed in position with reference to the edge

of the platform to allow the sections of the pipe when removed to be readily guided into said spaces of the finger board.

When it is desired to shift the finger board the motor 60 is set in operation so that the gear 62 will revolve the ring gear 44. Since the ring gear is connected to the shaft 43 the gear 45 will rotate the gear 46.

In view of the fact that the outer end of the rod 48 is threaded into a central opening in the gear 46 said gear would tend to move toward or away from the motor 60, depending upon the direction of rotation of said motor which is of the reverse type. However, the gear 46 is connected to the outer end of the guide or track 35 by means of an annular groove 51, the arms 53, and the lugs 52 disposed in the groove 51 in the hub 50 connected to the gear 46. Thus, the gear 46 may be revolved but will be maintained in position so that the threaded portion 47 of the rod 48 will cause the rod to be moved longitudinally in either direction in the guide 35, thereby moving the member 39 and likewise the connected fingers 18. Thus, it will be seen that the finger board will be conveniently positioned with respect to the platform 15 for the convenience of the operator.

The platform 15 is removably connected to the supporting structure by means of bolts 20 by tightening the nut 22. When the nuts are loosened the hooked portions 23 of the bolts 20 may be released from the bars 12, whereby the platform may be raised or lowered as desired.

For the purpose of raising or lowering the platform an eye 26 is provided which normally is housed within the opening or depression 25 of the platform. A hook on the chain of a hoist is adapted to be received by the eye 26 for drawing the platform 15 upwardly or for lowering the platform to the proper horizontal level.

It will be noted from Fig. 8 that the eye 26 normally rests in the pocket 25 below the upper surface of the platform so that there will be no danger of the operator being tripped by the same.

I claim:

1. A device of the class described comprising spaced supports, a tubular member carried at its ends by the supports and provided with a longitudinal slot, a slidable means in the tubular member, spaced fingers secured to the slidable means and projecting through the slot and means for moving the slidable means and fingers in the tubular means, said spaced fingers being adapted to support stands of pipes.

2. A device of the class described comprising spaced supports, a tubular member carried at its ends by the supports and provided with a longitudinal slot, a slidable means in the tubular member, spaced fingers secured to the slidable means and projecting through the slot, a shaft connected to the slidable means and having a threaded portion, a nut on the threaded portion, and means for rotating the nut for causing the shaft and slidable means to be moved in either direction in the tubular means for shifting the fingers as a unit back and forth.

3. A device of the class described comprising spaced supports, a tubular member carried at its ends by the supports and provided with a longitudinal slot, a slidable means in the tubular member, spaced fingers secured to the slidable means and projecting through the slot, a shaft connected at one end to the slidable means, the other end being threaded, a gear having a threaded

70 central opening receiving the threaded end of

the shaft, means retaining the gear against lateral movement, and means rotating the gear to cause reciprocation of the shaft and sliding of the connected fingers.

4. A device of the class described comprising spaced supports, a tubular member carried at its ends by the supports and provided with a longitudinal slot, a slidable means in the tubular member, spaced fingers secured to the slidable means and projecting through the slot, and means for moving the slidable means and attached fingers towards or away from the platform and including a rotatable means, a rod connected at one end with the slidable means, the other end of the rod being threaded into a passage in the rotatable means, means supporting the rotatable means against lateral displacement on an end of the tubular member, and means rotating the rotatable means for causing longitudinal shifting of the slidable means in the tubular member.

5. The combination with a well derrick, comprising cross pieces and a worker's platform supported thereon at one side of the derrick, of a finger board comprising a series of spaced fingers forming a pipe rack extending across the platform and means for moving the board transversely of the platform to successively expose the spaces between adjacent fingers outwardly from the edge of the platform for the reception of stands of pipe lengths placed in contact with the edge of said board.

6. The combination with a well derrick having cross pieces and a worker's platform supported horizontally thereon having an inner edge lo-

cated at one side of the vertical center line of the derrick for supporting vertical stands of pipe placed against it, of a finger board extending transversely above one end of said platform and comprising spaced fingers, and means for intermittently moving the board to successively align the spaces between its adjacent fingers with said inner edge of the platform.

7. A finger board for stacking pipe lengths in well derricks comprising a frame extending across the derrick and adapted to be supported in a horizontal position thereon forming a guideway and having at one end a gear with a threaded hub, bearings on the frame, a shaft carried therein carrying a pinion meshing with said gear, means for rotating the shaft located at the opposite end of said frame, a slide carried in the guideway of the frame, a threaded shaft extending from the slide into the hub of the gear and spaced rack fingers extending laterally from said slide.
